CIRCUMROTARY RIDING DEVICE

Filed July 28, 1928

FIG. 2

UNITED STATES PATENT OFFICE

EMERY E. CLARK, OF TOPEKA, KANSAS

CIRCUMROTARY RIDING DEVICE

Application filed July 28, 1928. Serial No. 296,025.

My invention relates to a circumrotary riding device.

The object of my invention is to provide a circumrotary riding device comprising a 5 platform rotatably mounted on a vertical shaft and being rotatable by reason of chains connected to an offset portion of the shaft.

A further object of my invention is to provide a removable securing means for the 10 hood.

A still further object of my invention is to provide a differently positioned angle for the eccentrically positioned stationary crank.

A still further object of my invention is 15 to provide a sleeve on the center post to avoid raising of the intermediate ends of the platform timbers, and also to show simplicity of construction for the horizontal support of the platform timbers and connecting means 20 for the railing to the timbers.

A still further object of my invention is to provide a removable means for the panels of the conical portion of the structure, terminating 25 at the inside of the annular platform, and also means by which one or more of the panels may be removed.

These and other objects will hereinafter be more fully explained, reference being had 30 to the accompanying drawings forming part of this specification, wherein like characters will apply to like parts throughout the different views.

Referring to the drawings:

Fig. 1 is an elevation of the machine, partly 35 in section, taken along line 1 in Fig. 2.

Fig. 2 is a plan view, parts removed for convenience of illustration.

Fig. 3 is an enlarged sectional view taken 40 on line 3—3 in Fig. 1.

Fig. 4 is a fragmentary plan view of one of the standards, carrying rod, and beam.

The invention herein disclosed consists of 45 a frusto-conical hood 1 having an aperture at the frustum end to engage over the center post 2. The opposite or lower end of the hood rests snugly on the panels 3, which function as an enclosure and form a conical body extending from the annular platform 4 and terminating near the center post, as 50 shown in Fig. 1.

In Fig. 2 is shown a panel 3' removably arranged, the said panel having a plate 5 securely attached thereto by means of screws 6; the ends of the plate lap well onto the adjacent panel on each side, and are attached 55 thereto by screws 7, the plate being of sufficient width to extend well under the conical hood, as shown by dotted lines A, the opposite side being exposed as accessible means to the said screws. All other panels are 60 attached by a plate 8, as shown in Fig. 2, said plate secured to the adjacent panels by means of screws 9. The opposite end of the panels fit snugly against the inner edge of 65 the annular platform and against the standards 10, by which means the lower ends of the panels cannot be raised until the upper ends have been released by the removal of their respective screws. The intermediate edge portions of the panels are carried by a 70 U-shaped cleat 11, the sides of the cleat fitting snugly on the carrying rods 12; the sides of the cleat extend outward as at B, functioning as a bearing for the edges of the panels as 75 shown in Fig. 3, the panels loosely engaging thereon. The lower ends of the rods 12 extend downward and are bent obliquely to extend through an aperture 13 in the right angle bent end C of the standard, and through an aperture in registry therewith in the beam 80 14, and being secured by a nut 15 at the lower end thereof, by which means the railing 16 is secured to the said beam simultaneously, and simultaneously supporting the beams in horizontal alignment. It will be understood that 85 the upper ends of the rods 12 are securely attached to a plate 12', said plate bearing on the upper portion of a ball bearing and rotatable therewith, the lower portion of the bearing being rigidly attached to the post, by 90 which means the structure is rotatably arranged; and to avoid rocking, the beams radially extend from the center post, and the inner ends thereof are secured to a plate 14', the said plate being apertured to revolve 95 freely on the center post. I have also placed a collar to engage firmly on the said post as a means to prevent downward movement of the inner ends of the beams. As a means to prevent upward movement of the inner ends of 100

the beams, a sleeve 2' is placed on the center post, and being of sufficient length to extend from the beam members to the under side of the ball bearing.

5 As a means to prevent the removal of the conical hood, I have placed a collar 17 threadedly engaging on the upper end of the post. The said collar also functions as a reinforcement for the apertured end of the post, which 10 provides a seat for the eccentrically positioned stationary crank 18, it being understood that considerable strain is placed on the crank when the machine is being rotated. It will also be understood that the collar does 15 not bind snugly on the frustum end of the hood, but is merely in close proximity thereto, so that the hood is free to revolve with the body of the machine.

In this application I have shown a crank 20 18, which is rigidly attached to the center post 2, the said crank having a lateral bend as at D to a vertical portion, on the outer end of which is positioned a disc-like member 19 rotatably engaging thereon as 25 pendant supporting means for a plurality of chains or cords 20, functioning as pulling means by occupants to rotate the machine, all of which was disclosed by my former application, hereinbefore referred to. However, in 30 the former application, the lateral bend referred to is positioned in parallelism with the conical form; but it is found that by raising this portion of the crank as herein set forth, all danger of being wedged between the bend 35 and the cone is eliminated.

It will be understood that the collar and hood, as removed, are free to follow the curvature of the crank by removing the disc member 19, and by moving disc 19. This arrangement eliminates the removal of the 40 crank when the bearing is to be investigated for repair or oiling, and other accessible means is the panel heretofore referred to, in which case workmen can enter without difficulty.

Such modifications may be employed with reference to varying the curvature of the crank, or the extent and pitch of the conical hood without departure from the spirit of 50 the invention; and such other modifications may be employed as lie within the scope of the appended claims.

Having fully described my invention, what I claim as new and desire to secure 55 by Letters Patent is:

1. In a circumrotary riding device, a structure of the kind described comprising an annular platform, a frustoconical portion, a vertical center post, standards and railing 60 on the platform, the frusto-conical portion intermediately positioned to the platform and upwardly extending, and the center post functioning as positioning means around which the platform and conical portion 65 revolve, a plurality of rods radially positioned

and in parallelism with the conical portion, the lower or outer ends of the rods attached near the inner peripheral edge of the platform to carry the same and simultaneously attach the railing standards, a plate carried by a ball bearing, the ball bearing positioned on the center post and rotatable thereto, the opposite or inner ends of the rods attached to the plate, a conical hood positioned on the frustum end of the first said conical portion, the upper end of the hood being apertured to revolve on the post, and a collar threadedly engaging on the upper end of the post as securing means for the hood against removal, the hood rotatable with the first said conical portion and functioning as a closing means for the top.

2. In a circumrotary riding device, a structure of the kind described comprising a plurality of radially positioned beams and an annular platform positioned on the outer ends of the beams, a center post, and a plurality of radially positioned rods, and a ball bearing attached to the post as carrying means for the structure, means to attach the inner ends of the rods to the bearing, the outer ends being attached to the beam adjacent the platform, and a plate rotatable on the post and to which the inner ends of the beams are attached, by which means rocking of the structure is obviated, a saddle member to engage on each of the rods, each saddle having an outwardly extending flange on each side thereof, a panel converging toward the inner end to close the space between the rods and adapted to rest on the flange side of the saddles respectively, and plates connecting the upper ends of each of the panels as securing means therefor, the ends of the panels being spaced from the center post, a conical hood to engage snugly on the ends of the panels as closing means for the space, the upper end of the hood being apertured to snugly but rotatably engage on the post, a collar threadedly engaging on the post to prevent upward movement of the hood, a stationary crank member having an upward extension eccentrically positioned to the post, and rigidly attached thereto, and chains rotatably attached to the upper end thereof as a pulling element by occupants on the platform to rotate the structure in either direction.

3. In a circumrotary riding device, an annular platform, a polygonal conically disposed enclosure within the annular platform, 120 said enclosure being divided into panels removably arranged, and a conical hood to fit snugly on the upper ends of the panels of said enclosure and revolvable therewith, a center post having a ball bearing positioned 125 near the upper end thereof, and means to carry the platform and enclosure by the bearing as rotatable means on the post.

4. In a circumrotary riding device, an annular platform, and a frusto-conical en- 130

closure centrally positioned on the platform, and a post stationarily positioned and having a threaded aperture axially positioned in the upper end thereof, the said post having a ball bearing spaced from the upper end thereof, the bearing being in two parts, an upper and a lower portion, the lower portion being attached to the post, the upper portion rotatably arranged, and a plate attached to 5 the upper portion, to which radially positioned rods are attached at the inner ends, the outer ends attached near the inner edge of the platform, saddle members on each of the rods, the said members having a flange outwardly extending, panels positioned between the rods to engage on the flanges of the saddle respectively, the panels extending inward and upward, the ends being spaced from the post, a conical hood rotatably positioned 10 on the post, the lower end being lapped over the ends of the panels, fitting snugly thereon, a collar threadedly engaging on the upper end of the post to prevent upward movement of the hood, and as a re-enforcing means for 15 the apertured upper end of the post, a crank-like member threadedly engaging in the aperture, the upper end of the crank being positioned eccentric to the post and having on the upper end thereof a member revolvably attached, the member having a plurality of chains or the like attached thereto as means by which occupants of the platform will cause 20 said platform to revolve.

5. In a circumrotary riding device, a center post having an offset portion on the upper end thereof eccentrically positioned to the post, a plurality of flexible members, the said flexible members attached to a rotatably mounted member on the offset portion of said 25 post, an annular riding mechanism rotatably carried by the post, the rotations thereof actuated by occupants of the riding mechanism pulling the flexible members.

6. In a circumrotary riding device, a circular platform, a vertical post having an offset on the upper end, the circular platform rotatably mounted on the vertical post, a plurality of chains connected at one end and trunnioned on the offset portion of the post 30 substantially as shown.

7. In a device of the kind described, a circular platform having a conical portion concentric therewith and extending upward, a vertical post having an offset portion at its 35 top, the platform being rotatably mounted on the vertical post, a disc trunnioned on the offset portion of the post and rotatable thereto and having a plurality of apertures near its periphery, a plurality of chains, one end 40 of the chains being connected to the said discs in the apertures and the other end being free, and the chains functioning as propelling means for the rotation of a platform in the manner described.

8. In a circumrotary riding device, a coni-

cal body having an annular platform on the base thereof, a post vertically positioned on which the body rotates and an eccentrically positioned portion for the upper end of the post, means to pendantly support flexible members on the eccentric portion for the purpose described. 70

In testimony whereof I affix my signature.
